UNITED STATES PATENT OFFICE.

WALDEMAR DYRSSEN, OF TARRYTOWN, NEW YORK.

METHOD AND APPARATUS FOR HEATING AIR FOR BLAST FURNACES.

Application filed November 20, 1922. Serial No. 602,304.

To all whom it may concern:

Be it known that I, WALDEMAR DYRSSEN, a citizen of the United States, and resident of Tarrytown, New York, have invented certain new and useful Improvements in the Method and Apparatus for Heating Air for Blast Furnaces, of which the following is a specification.

This invention relates to an improved 10 method and apparatus for heating the air blast supplied to blast furnaces and also to improvements in the construction of stoves used to heat the blast.

Heretofore there have been two typical 15 methods employed for heating the air for blast furnaces. The simplest and oldest method consisted briefly in passing air through iron pipes which were externally heated by the combustion of blast furnace 20 gas. Such method is not suitable for heating the blast to a high temperature, required in modern practice, as the iron pipes are quickly destroyed or cracked by the excessive heat. The use of iron pipes is not 25 suitable where a high pressure air blast is used on account of the liability to leakage, and in modern blast furnace practice the air blast is usually supplied at a high pressure. For these reasons the use of iron pipes 30 for heating the blast has been practically abandoned.

The second and more generally used method of heating the blast consists in passing the air through stoves filled with bricks 25 forming a checkerwork which has previously been heated to a high temperature by burning blast furnace gas in the stove. When heating the air blast in this way it is necessary to have at least two stoves for each 40 blast furnace as the checkerwork in one must be heated while the checkerwork in the other is giving up its heat to the air blast. In most modern plants five stoves are built for each blast furnace, one or two 45 being used to heat the air blast and two or three being heated by the blast furnace gas for subsequent use, and the fifth stove being held in reserve for use in the event of a breakdown or repairs to any of the other 50 stoves. These stoves are of large dimensions being approximately 100 feet in height and 25 feet in diameter and each containing several million pounds of bricks. Suitable 55 valves for part of the usual installation whereby one or more stoves can be alternately used to heat the blast, or be supplied

with blast furnace gas and air for heating the stove. The valves for alternating the use of the stoves are manipulated about once every hour and there is considerable 60 labor connected with this operation.

With this method, the temperature of the blast is not constant because at the beginning the checker bricks are hotter and consequently heat the air blast to a higher 65 temperature at the beginning of a period, than at the end of a period after the bricks have been cooled down by the blast. Such method of heating is rather inefficient and practical operation shows that only 50 to 70 70 per cent of the heat in the blast furnace gas is effective for heating the checkerwork. This inefficiency is due partly to the large surface exposed to atmosphere by the several stoves and partly due to losses in changing 75 the stoves over from burning gas to heating the blast. Further losses are due to leaky hot blast valves, it being known to those skilled in the art that it is extremely difficult to keep these valves tight because 80 of the high temperatures and pressures in modern blast furnace practice.

My improved method will overcome the above objections and I can secure a heating 85 efficiency as high as 80% or more and only 85 one stove is required for each blast furnace, and this stove is smaller than any one of the four or five heretofore provided to accomplish the same function.

It is possible to heat the air for the blast 90 furnace to a high enough temperature by direct heating by the use of brick pipes through which hot gases are passed. Brick pipes can stand a much higher temperature than iron pipes but it is difficult to use 95 brick or tile pipes exclusively for heating the air blast because of the pressure used in modern blast furnace practice, it being apparent that brick or tile pipes would not withstand the high pressure without bursting or leaking at the joints.

According to my method, however, I can 100 use brick pipes successfully as I compress the gas and air necessary for combustion in the stove or heating apparatus to substantially the same pressure as the blast and thereby eliminate any difference in pressure 105 between the hot gases within the pipes and the blast outside the pipes, or vice versa. I can use pipes in the stove constructed partly 110 of refractory material such as brick or tile and partly of iron or other metal. Pref-

erably I use iron pipes to heat the blast to about 700 degrees F. and brick pipes to heat the blast from 700 degrees F. to the highest temperature required or to about 5 1300 degrees F. The use of iron pipes at the lower temperature is of particular advantage because the heat can be transferred through the walls of iron pipes about two to five times faster than through brick pipes. 10 I use brick or other refractory pipes in the hottest zone of the stove as they will not be damaged by the excessive heat. My method will be understood and the construction of my improved apparatus will be clear 15 from the following specification when read in connection with the accompanying drawings in which—

Fig. 1 is a diagrammatic view showing a blast furnace, a stove for heating the blast 20 therefor and other associated apparatus;

Fig. 2 is a vertical longitudinal section through a stove illustrating features of my invention;

Fig. 3 is a section on line 3—3 of Fig. 2; 25 Fig. 4 is a section on line 4—4 of Fig. 2; Fig. 5 is a section on line 5—5 of Fig. 2; Fig. 6 is an enlarged detail illustrating the construction of pipes formed partly of refractory material and partly of metal; 30 Fig. 7 is an inverted plan of a fitting used to couple the brick pipes to the metal pipes and Fig. 8 is a modification of fitting illustrated in Fig. 7.

Fig. 9 is an enlarged detail view; Fig. 10 35 illustrates a modification.

Referring first to Fig. 1 the blast furnace 10 is of the usual type and the blast furnace 10 passes through downcomer 12 to the usual dust catcher 14 and from there to the usual scrubber 9 where the gas is cleared 40 and cooled to approximately atmospheric temperature. From the scrubber part of the gas passes by way of pipe 16 to a compressor 18 and by pipe 20 and Y-fitting 22 45 to branches 24 and nozzles 26. These nozzles discharge the gas through ports 28 in a tangential direction as indicated in Fig. 5. The nozzles 26 project through openings formed in extensions 30 which are connected with an air supply branch 32. The 50 branches 32 communicate with an air supply pipe 34 which through a port 36 is in communication with the heating chamber 38 of the hot blast stove indicated as a 55 whole by the numeral 40. The stove is built with an outer shell 41 of suitable metal and is lined with suitable insulating brickwork 60 refractory lining 43. In addition to the heating chamber 38, the stove is provided with a combustion chamber 42 which is separated from the heating chamber by a diaphragm or wall 44. At its lower end, the 65 stove is formed with a waste gas chamber 46 which is separated from the heating chamber by a wall or diaphragm 48. The

combustion chamber 42 is in communication with the waste gas chamber 46 through a multiplicity of pipes indicated generally by numeral 50. These pipes are of sectional formation, the upper portions 52 being 70 formed of brick, tile or other refractory material such as carborundum and the lower portions 54 being made of iron, stainless steel or other suitable metal. The tile pipes 50 are joined to the metal pipes 54 by means 75 of fittings 56 and said fittings are provided with two or more branches 58 as shown in Figs. 6 to 8 which are adapted to engage suitable sockets formed in the ends of the pipes 54. In this way I can use tile pipes 80 of generous dimensions and connect each tile pipe with two or more metal pipes as will be understood.

The cold air blast is supplied through a pipe 60 by a suitable blowing engine 62, the 85 air entering through ports 64 formed in the lower part of the heating chamber 38. The air circulates through the heating chamber around the pipes 54 and 52 and is heated by contact with said pipes, it being understood 90 that the blast furnace gas introduced through the nozzles 26 burns in the combustion chamber 42 with air supplied from the heating chamber 38 through port 36 and pipe 34 and that the products of combustion pass at approximately the same pressure as the air blast, through the pipes 52 and 54 into the waste gas chamber 46.

The cold blast is supplied to the pipe 60 100 by the blowing engine 62 at the usual pressure required in modern blast furnace practice of 15 to 20 pounds above atmosphere and the compressor 18 raises the pressure of the blast furnace gas supplied to the combustion chamber 42 to slightly above the 105 pressure of the blast. The pipes 34 and 32 supplying combustion air from the partly heated blast in heating chamber 38 are of such generous dimensions as are also the ports 28 that there is practically no frictional pressure loss, hence it is apparent 110 that the pressure in the combustion chamber and inside and outside the pipes is equalized and there is no appreciable strain exerted upon the piping from the blast pressure. The slightly higher pressure of the gas is consumed in nozzles 26 for effective mixing with the air in order to obtain perfect and rapid combustion.

Suitable baffle plates 64 are placed at intervals in the heating chamber and these baffles are provided with openings 66 which are arranged so that the openings in one plate are staggered with relation to those of the next so that the air blast is compelled 115 to travel a circuitous path through the heating chamber and thereby come in intimate contact with the pipes heated by the blast furnace gas. The holes 66 at the inner zone 120 of the plates 64 are preferably larger than 130

those at the outer zone in order to distribute the blast properly over the heating surfaces. The heated air blast leaves the stove by way of hot blast ports 68 which are connected 5 to a suitable header 70 and the blast is conveyed by a pipe 72 to the bustle chamber 74 of the blast furnace.

If desired I may provide a branch pipe 76 indicated in Fig. 10 connecting the pipe 10 60 with the pipe 34 so as to supply combustion air to the chamber 42 without passing such air through the stove, and the pipe 76 will be provided with a butterfly valve 78 for either cutting off the supply therethrough 15 or for controlling the volume of air so supplied.

The waste gases or products of combustion which pass into the chamber 46 will contain an appreciably higher amount of mechanical 20 energy than was used for the compression of the gas and air before combustion as their temperature is in the neighborhood of from 400 to 500 degrees F. I propose to utilize this energy and to these ends I have illustrated 25 an outlet 80 having a nozzle 82 the outlet orifice area of which can be controlled by valve 84 normally held in the wide open position by a spring, not shown, and adapted to be moved inwardly by any suitable means 30 such as a thumb screw 86. This nozzle directs the jet of gas against the vanes of a turbine rotor 88 enclosed in a suitable casing 90, the spent gases escaping to the atmosphere or being lead to a stack from the outlet 35 connection 92 formed in the casing. The rotor 88 is coupled to an armature shaft 92 of a suitable electric generator 94 and said generator delivers sufficient energy to drive the compressor 18 and supply power to the 40 electric power system of the plant.

From the foregoing it is clear that my invention contemplates compressing the blast furnace gas and supplying it to the combustion chamber 42 of the stove wherein it is 45 mixed with part of the blast air. It is apparent that as the products of combustion pass downwardly through the pipes 52—54 that they will be intensely heated and that the blast of air circulating through the chamber 38 around said pipes will be thoroughly 50 heated. The hot blast will be discharged through the pipe 72 and conveyed to the blast furnace 10. The metallic portions of the pipes as indicated at 54 are in the cooler 55 zone of the stove, remote from the combustion chamber, while the pipes of refractory material are adjacent to the combustion chamber and hence in the hottest zone. This arrangement is advantageous as the metallic 60 pipes in the cooler zone are capable of effecting a more rapid transfer of heat to the air flowing around them than pipes of brick or other refractory material would be capable of. Furthermore the refractory pipes 65 in the upper zone are capable of withstand-

ing the excessive heat which often reaches a temperature of 2500 degrees F. and in this zone because of the high heat it is not necessary to use material capable of transmitting heat so rapidly. In view of the fact that the 70 gas and the air used for combustion is raised to a pressure substantially equal to that of the cold blast it is apparent that the pressure on the inside and outside of the pipes is 75 equalized, hence no undue strain from the blast pressure is exerted which would tend to fracture either the metal or refractory pipes.

In the above description I have described the stove as being provided with a combustion chamber so arranged that the products of combustion are passed through pipes to heat an air blast which circulates around the exterior of the pipes. It is to be understood, however, that if desired I may arrange the 80 stove so that the air blast will pass through the pipes and the products of combustion pass around the exterior of the pipes or any other equivalent arrangement or apparatus 85 for the direct heat interchange between two 90 gases separated from each other can be used.

In this description I have only referred to blast furnace gas as fuel. This is the natural fuel to use as it is always available as soon as the blast furnace is in operation. 95 However I may also use any other kind of fuel such as tar or fuel oil. In such case I can substitute the gas compressor 18 with a fuel pump. I can also use powdered coal, producer gas, coke-oven gas, or natural gas. 100 The compressors 18 and 62 can be of any common type such as gas, steam or electrically driven cylinder engines or steam turbine or electromotor driven turbine compressors. The turbine 90 might also be substituted with a cylinder engine. This power 105 unit does not form an essential part of the installation and under certain conditions it might not be desirable to utilize the pressure energy of the waste gases and in such a case 110 only a nozzle or valve is used. It is evident that regulating of the opening of the nozzle 82 influences the combustion of the gas in chamber 42. If it is open too much an excess amount of air will be drawn through pipes 115 34 and 32 and if the opening is too small the gas will not be completely burnt. I propose to install a CO₂ recorder in pipe 80 in order to manually or automatically regulate the valve 84 so that I obtain ideal combustion in 120 all cases. In order to regulate the temperature of the blast to the furnace I vary the amount of gas compressed in 18. Under certain conditions I also propose to arrange the waste gas motor 90, generator 94 and compressor 18 in one unit. It is also possible to make compressor 62 with its motor part of this unit in order to reduce the cost of the equipment. It is obvious that it is desirable 125 to install the usual mechanically and auto- 130

4
matically operated valves in the gas and blast pipes and the usual automatic safety control switches for the compressors in order to prevent possible explosions and to insure

5 safety in operation.

While I have described with great particularity a specific heating stove and certain apparatus for carrying out my method, it is not to be construed that I am restricted 10 to the particular method described or to the construction of the apparatus shown, as various changes may be made by those skilled in the art without departing from the invention as defined in the appended 15 claims.

What I claim is:

1. The method of heating the air blast for blast furnaces which consists in simultaneously passing the air blast and combustible 20 gas or fuel in separate streams through a heating apparatus and compressing the air blast and the combustible gas or fuel and burning said fuel in said heating apparatus under substantially the same pressure as the 25 blast air to be heated in said heating apparatus.

2. The method of heating air for blast furnaces which consists in compressing blast furnace gas to substantially the same pressure 30 as the cold blast and burning said gas with air under substantially the same pressure and passing the products of combustion under substantially the same pressure through a heating apparatus counter-current 35 to the air blast to heat the latter and conveying the heated air to the blast furnace.

3. The method of heating air for blast furnaces which consists in conveying gas from a blast furnace to a compressor and 40 raising the pressure thereof thereof to substantially or approximately the same pressure as the air blast, conveying said gas to a surface heating apparatus and mixing it with part of the cold air blast for combustion 45 and burning the mixture under substantially or approximately the same pressure as the air blast, passing the products of combustion under the same pressure through pipes in one direction and passing the air blast 50 around the pipes in the opposite direction to heat the air blast and conveying the heated blast to the blast furnace.

4. The method of heating air for blast furnaces which consists in supplying gas to 55 a heating apparatus at a pressure above atmosphere, supplying an air blast to the apparatus at substantially or approximately the same pressure as the gas, mixing said gas with air, burning the mixture in said 60 heating apparatus and passing the products of combustion through the heating apparatus counter-current to the air blast to heat the latter.

5. The method of heating air for blast 65 furnaces which consists in supplying blast

furnace gas under pressure to the combustion chamber of a heating apparatus; supplying an air blast to said heating apparatus at substantially the same pressure as said blast furnace gas mixing part of the 70 air from said blast with the gas to support combustion and passing the products of combustion through pipes in the heating apparatus to heat the air blast.

6. An apparatus of the class described 75 having a combustion chamber, means for supplying blast furnace gas under pressure to said combustion chamber, means for passing the products of combustion under pressure from said chamber through the 80 apparatus in one direction, and means for passing an air blast at substantially the same pressure as the products of combustion through said apparatus in the opposite direction so as to heat said air blast. 85

7. An apparatus of the class described having a combustion chamber, means for supplying blast furnace gas under pressure to said combustion chamber, means for passing the products of combustion from said 90 chamber through the apparatus in one direction, means for passing an air blast through the apparatus in the opposite direction so as to heat said air blast and means for supplying part of the air blast to the 95 combustion chamber to support combustion of the blast furnace gas.

8. In an apparatus of the class described, a structure having a combustion chamber, means for supply blast furnace gas at pressure above atmosphere to said combustion chamber, a multiplicity of pipes for conveying the products of combustion from said 100 chamber through the structure, and means for passing an air blast through the structure in contact with said pipes at substantially the same pressure as that of the blast furnace gas. 105

9. In an apparatus of the class described, a structure including a combustion chamber, means for supplying blast furnace gas under pressure to said combustion chamber, a multiplicity of pipes communicating with said combustion chamber and arranged to convey the products of combustion through 110 the structure, said pipes being formed in sections of refractory material and of metal, the refractory sections being located in the hotter zone and the metallic sections being located in the cooler zone, and means for 115 passing an air blast through the structure in such manner that it is heated by contact with said pipes. 120

10. In an apparatus of the class described means for heating the air supplied to a 125 blast furnace, comprising a stove adapted to burn compressed blast furnace gas, said stove having a blast inlet and a hot blast outlet and a multiplicity of pipes arranged to convey the products of combustion 130

- through the stove, said pipes being of sectional formation and having refractory and metallic sections, the metallic sections being located in the cooler zone of the stove 5 and the refractory sections being located in the hotter zone.
11. An apparatus adapted to heat the air supplied to a blast furnace, including a combustion chamber adapted to receive blast furnace gas under pressure, an inlet 10 for the comparatively cold air blast, pipes communicating with said combustion chamber adapted to heat the cold air blast, a hot air blast outlet adjacent the combustion chamber, a waste gas chamber remote from said combustion chamber and communicating therewith by means of said pipes and means for supplying air heated by said pipes to said combustion chamber to support combustion of the blast furnace gas supplied thereto.
12. An apparatus adapted to heat the air supplied to a blast furnace including a combustion chamber, a waste gas chamber, an air heating chamber between the combustion and waste gas chamber, pipes 20 connecting the combustion and waste gas chambers, means for supplying blast furnace gas under pressure to said combustion chamber, means for supplying air to said heating chamber at substantially the same pressure as the gas and means for equalizing the pressure of the blast furnace gas and the air blast to prevent leakage through said pipes.
13. In combination with a blast furnace, a single stove for continuously heating the air blast supplied to said furnace, means for continuously conveying gas from said blast furnace to a compressor and raising the pressure thereof, a combustion chamber in said stove, means for continuously supplying air under pressure to said combustion chamber to support combustion of said gas, pipes for conveying the hot products of combustion through the stove and means for continuously passing a blast of air through the stove in a circuitous path around said pipes to heat the blast.
- In witness whereof I have hereunto signed my name.

WALDEMAR DYRSSEN.
